(57) **CLAIM**

The ornamental design for an apparatus with integrated sensor for the determination of fluid properties, as shown and described.

DESCRIPTION

FIG. 1 is an isometric view of the apparatus with integrated sensor for the determination of fluid properties;

FIG. 2 is a top plan view of the apparatus with integrated sensor for the determination of fluid properties of FIG. 1;
FIG. 3 is a front elevation view of the apparatus with integrated sensor for the determination of fluid properties of FIG. 1;

FIG. 4 is a rear elevation view of the apparatus with integrated sensor for the determination of fluid properties of FIG. 1;
FIG. 5 is a left side elevation view of the apparatus with integrated sensor for the determination of fluid properties of FIG. 1; and,

FIG. 6 is a right side elevation view of the apparatus with integrated sensor for the determination of fluid properties of FIG. 1.

The phantom lines and areas shown in the figures are for illustrative purposes only and form no part of the claimed design.
